UNITED STATES PATENT OFFICE

HARRY W. LINDSEY, JR., OF EVANSTON, ILLINOIS, ASSIGNOR TO COLUMBUS HANDLE & TOOL CORPORATION, OF COLUMBUS, INDIANA, A CORPORATION OF INDIANA

DESIGN FOR A TOOL HANDLE

Application filed July 26, 1930. Serial No. 36,485. Term of patent 14 years.

To all whom it may concern:

Be it known that I, HARRY W. LINDSEY, JR., a citizen of the United States, residing at Evanston, county of Cook, State of Illinois, have invented a new, original, and ornamental Design for Tool Handle, of which the following is a specification, reference being had to the accompanying drawings, forming a part hereof.

Figure 1 is a perspective view of the tool handle, showing my new design;

Fig. 2 is a section along the line 2—2 in Fig. 1, looking in the direction of the arrows;

Fig. 3 is a one-half cross-section along the line 3—3 in Fig. 1, looking in the direction of the arrows.

The dominant feature in which my inven-

tion more particularly resides is the flattened contour of the sections which together form the outer faces of the forks of the handle, in relation to the connection of such face sections of the forks with the cups which receive the transverse grip portion of the handle and the connection of such sections with the tubular lower portion of the handle,—the central section of such face merging into the flat bottom of the particular cup and the side sections merging into the flaring side portion of the cup, and all sections intersecting the cylindrical face of the lower portion of the handle on curved lines.

I claim:

The ornamental design for a tool handle as shown and described.

HARRY W. LINDSEY, JR.
